(74) Attorney, Agent, or Firm—Michael A. Catania; Elaine H. Lo

(57) **CLAIM**

The ornamental design for a putter head, as shown and described.

DESCRIPTION

FIG. 1 is a bottom perspective view of a putter head; and, FIG. 2 is a bottom plan view thereof.

The broken line showing is for illustrative purposes only and forms no part of the claimed design.

1 Claim, 1 Drawing Sheet
